Attorney

UNITED STATES PATENT OFFICE.

JOHN McDONALD, OF MONTREAL, QUEBEC, CANADA.

SHOE-FASTENING DEVICE.

1,336,146.

Specification of Letters Patent.

Patented Apr. 6, 1920.

Application filed November 14, 1919. Serial No. 337,948.

To all whom it may concern:

Be it known that I, JOHN McDONALD, a subject of the King of Great Britain, residing at Montreal, Province of Quebec, 5 Canada, have invented certain new and useful Improvements in Shoe-Fastening Devices; and I do hereby declare that the following is a full, clear, and exact description of the invention, such as will enable others 10 skilled in the art to which it appertains to make and use the same.

The present invention has relation to shoe fastening devices and more particularly appertains to a combined button and button- 15 ing attachment for shoes.

The principal object of the invention is to provide a combined button and attachment element therefor, whereby it is secured to the shoe and means for utilizing 20 the attaching element for fastening or inserting the button within the button-hole.

Another object of the invention is to provide a combined shoe button and upper fastening device that is capable after actuation 25 to insert the button within the button-hole of the opposing upper, of being concealed between the upper sections of the shoe to which it is attached.

The invention has been illustrated in its 30 preferred embodiment in the accompanying drawings, wherein;

Figure 1 is a detailed elevational view of a shoe button and fastening element connected thereto, with a portion of the shoe 35 upper and an eyelet in section;

Fig. 2 is an elevational view illustrating the button fastening element inserted through the button-hole; and,

Fig. 3 is a detailed view of the device in 40 locked position with the shoe uppers and staple in section.

In carrying out the present invention, reference being had to the drawings in detail, there is provided a fastening member 10 for 45 each shoe button 11, which comprises a piece of wire bent at approximately its medial point to form the leg portions 12 and 13. Each fastening member 10 is adjustably connected to the staples 14 on the inner shoe 50 upper, by passing through the staple 14, whereby the upwardly curved part 14' of the latter is normally disposed within the medial bent portion of the fastening member 10. The leg portion 13, contiguous to 55 the medial bent portion of the fastening

member 10, curves upward and outwardly and has its end 15 bent outwardly at an angle to said leg portion 13. The leg portion 12, likewise adjacent the medial portion, is first slightly inclined downwardly and then upwardly and inwardly toward the leg portion 13 and has its end 16 disposed at an angle extending slightly upwardly. 60

The ends 15 and 16 of the fastening member 10 are attached to a composite shoe button 17 at the same time that the latter is 65 molded.

In operation to fasten or to button up the shoe, the button 17 will be inserted through a button-hole in the opposite upper 70 section of the shoe and at this time, the upwardly curved part 14' of the staple 14, will be disposed within the medial loop portion of the fastening member as illustrated in Fig. 2. Then the button 17 and fastening 75 member 10 to which it is connected are drawn entirely through the button-hole and the fastening member 10 is forced over and inwardly and is disposed flush with the end of the shoe upper carrying the staple 14, 80 to which it is connected.

The upwardly curved part 14' of the staple 14 will then be disposed within the curved portion of leg 12 at its point of intersection with the upwardly turned end 16, 85 as illustrated in Fig. 3.

Resultant of this action of using member 10 as a lever, so to speak, the outer upper in which the button-holes are located, is drawn or stretched over the inner or lower 90 upper.

The leg portions 12 and 13 of member 10 will then lie between the inner and outer shoe uppers, the upwardly directed end portions 15 and 16, will extend through the button-hole, and the button 17, attached thereto, will be disposed outside of the button-hole and consequently serve to prevent the disconnection of the said uppers, as in the manner of the usual buttons. 95

In this manner the buttons and buttoning elements 10, are attached to the shoe by the fastening members 14, and said button elements serve as a connecting medium for the button to the member 14 and likewise for 105 performing the closing function.

Having thus fully described my invention, what I claim as new and desire to secure by Letters Patent is:—

1. The combination with a shoe having 110

upper sections, of a button attached to one of said sections, a buttoning element secured to said button, and means for actuating said buttoning element to connect said upper sections together.

2. The combination with a shoe having upper sections, of a button secured to one of said sections and adapted for connecting said upper sections together, means connect-
10 ed to said button for fastening the same to the other of said upper section, and means for connecting said button to the shoe.

3. The combination with a shoe having upper sections, of a button carried by one of said sections and adapted for insertion 15 within a button-hole in the opposing section, a buttoner attached to said button and adapted for actuation to dispose said button within the button-hole, and means for concealing the buttoner upon the connection of 20 the said upper sections together.

In witness whereof I have hereunto set my hand.

JOHN McDONALD.
